UNITED STATES PATENT OFFICE.

ALVIN J. BASSETT, OF MILWAUKEE, WISCONSIN, ASSIGNOR TO SHARP-BASSETT GAS PRODUCER COMPANY, OF MILWAUKEE, WISCONSIN.

GAS-FILTER.

1,103,249.

Specification of Letters Patent. Patented July 14, 1914.

Application filed February 20, 1914. Serial No. 819,896.

To all whom it may concern:

Be it known that I, ALVIN J. BASSETT, a citizen of the United States, and resident of Milwaukee, in the county of Milwaukee and State of Wisconsin, have invented certain new and useful Improvements in Gas-Filters; and I do hereby declare that the following is a full, clear, and exact description thereof.

10 My invention has for its object to provide a simple, effective and economical gas filter and it consists in certain peculiarities of construction and combination of parts as set forth hereinafter with reference to the accompanying drawings and subsequently claimed.

In the drawings Figure 1 represents a central sectional view of a filter embodying the features of my invention, the section being indicated by line 1—1 of Fig. 3; Fig. 2, a similar sectional view of the filter taken upon a plane as indicated by line 2—2 of Fig. 3, and Fig. 3, a sectional plan view of said filter, with parts broken away, the section being indicated by line 3—3 of Fig. 1.

Referring by characters to the drawings, 1 represents a housing of the drum type, divided into upper and lower compartments, 2, 3, respectively, by a centrally apertured 30 partition-disk 4 having V-shaped intake and delivery ports 4', 4'', therein. The housing is closed at its top and bottom by caps 5, 6, respectively, having centrally disposed stuffing boxes 5', 6'. The walls of the lower compartment 3 are provided with oppositely disposed gas intake and discharge ports 7 and 8 respectively, for attachment to suitable supply and delivery pipe mains, not shown. A valve-disk 9 is seated upon the partition-disk 4 within the upper or filter compartment, the said valve-disk being provided 40 with oppositely disposed V-shaped ports 9', arranged to register with the partition-disk ports, whereby the flow of gas through the upper compartment is controlled. This valve-disk has secured thereto a valve-stem 10 that is journaled in the partition-disk apertures and also the lower cap stuffing-box 6', through which stuffing-box it extends, 50 terminating with a squared key-head 10' whereby said stem is manipulated. As best shown in Fig. 1, when the valve-disk ports 9' are in register with their companion partition-disk ports 4', 4'', the lower housing 55 compartment 3 is sub-divided by gate 11, in

such manner as to cut off communication between the intake and discharge ports 7 and 8, this gate being secured to the valve-stem.

The valve-disk 9 is centrally recessed for the reception of a trunnion 12 that forms 60 part of a rectangular filter frame 13 and the upper stretch of the same also carries a trunnion stud 12', which trunnion stud extends through the cap stuffing-box 5', terminating with a key-head 12''. The various 65 stretches of the filter frame are L shaped in cross-section and the vertical webs thereof have fitted thereto a metallic screen sheet 15 preferably constructed from a perforated plate. A second screen sheet 15' confines a 70 layer of filter material 16 that is interposed between the sheets, which filter material is preferably composed of glass-wool, as this substance has been found to produce the most efficient results.

75 The filter plates or screens have fitted thereto a rectangular follower frame 17, and the entire assemblage is confined by a series of bolts 17'. Hence it will be seen that a flat filter is produced which can readily be dismantled for cleaning and repairs, or renewal as the conditions may require.

The transverse stretches of the filter frame are arranged to have close fit relative to the inner face of the housing cap 2 and the corresponding face of the valve-disk 9, while the longitudinal stretches of said frame effect a practically closed joint relative to longitudinal ribs, which ribs project inwardly from the walls of the upper housing 90 compartment at a right angle to intake and discharge ports of the lower compartment.

In the operation, this filter, as shown, is aligned with the ribs and thus divides the upper or filter compartment in halves and the valve being turned to register the ports, gas under pressure will travel as indicated from the intake port 7 through valve controlled port 4' to the receiving half of the upper compartment. The gas is then forced 100 through the filter, whereby the tar is extracted therefrom and thereafter the cleansed gas is caused to flow into the lower compartment through the valve controlled port 4'' from which compartment it is carried off through 105 the discharge port. Should it be desired to cut out the filter, the valve stem 10 is manipulated, whereby the gate is swung open to establish direct communication between the intake and discharge ports 7 and 8 and 110

- coincident to this movement the valve disk will cut off communication with the upper housing compartment. As the gas comes in contact with the screen sheet in entering the filter, the tar product deposit thereon, will from time to time clog said screen sheet and to provide against such contingency the filter as a unit is given a half turn in order to reverse the screen sheet, whereby clogging 5 is avoided, it being understood that, as the gas passes through the outgoing screen, it tends to clear or blow out the choked screen apertures of that sheet which had previously 10 acted as a receiving screen.
- 15 I claim:
1. A gas filter comprising a housing having a ported partition disk therein dividing the housing into compartments one of which has a gas intake and a gas discharge port, a 20 stem projecting from the partition disk through the ported compartment of the housing, a gate carried by the stem for regulating communication between the intake and discharge ports, an oscillatory frame 25 mounted within the other housing compartment, a flat filter carried by the frame, and means for reversing the position of said filter frame.
  2. A gas filter comprising a drum-like 30 housing having a gas intake and a gas discharge port adjacent to one end and arranged opposite each other, a centrally apertured and ported partition-disk carried by the housing whereby the same is divided 35 into a gas receiving and discharge compartment and a filter compartment, a ported disk-valve revolvably mounted upon the par-

tition within the filter compartment, a stem carried by the valve-disk extending through the partition and receiving and discharge compartment, a gate carried thereby, a trunnioned frame mounted in the filter compartment arranged to form close contact with the walls of said compartment and valve-disk, and a flat filter carried by the 45 frame.

3. A gas filter comprising a drum-like housing having a gas intake and a gas discharge port adjacent to one end and arranged opposite each other, a centrally 50 apertured and ported partition-disk carried by the housing whereby the same is divided into a gas receiving and discharge compartment and a filter compartment, a ported disk-valve revolvably mounted upon the partition within the filter compartment, a stem carried by the valve-disk extending through the partition and receiving and discharge compartment, a gate carried thereby, a trunnioned frame mounted in the filter compartment arranged to form close contact with the walls of said compartment and valve-disk, screen sheets fitted into the frame 55 having filter material therebetween, and securing means for the filter sheets.

In testimony that I claim the foregoing I have hereunto set my hand at Milwaukee in the county of Milwaukee and State of Wisconsin in the presence of two witnesses.

ALVIN J. BASSETT.
